DIMERIZATION OF CONJUGATED DIENES

Paul F. Warner, Phillips, Tex., and James D. Maxwell, Bartlesville, Okla., assignors to Phillips Petroleum Company, a corporation of Delaware

No Drawing. Filed Aug. 5, 1957, Ser. No. 676,434

7 Claims. (Cl. 260—666)

This invention relates to an improved process for dimerizing conjugated dienes. In another aspect this invention relates to a process for the selective formation of dimers of conjugated dienes having from 4 to 6 carbon atoms per molecule. In one of its more specific aspects this invention relates to an improved process for the production of vinylcyclohexene by dimerizing 1,3-butadiene.

Conjugated dienes such as 1,3-butadiene, isoprene, piperylene and the like can be polymerized thermally without the benefit of catalysts. By properly controlling reaction conditions it is possible to selectively dimerize these conjugated dienes and reduce the amount of trimer, tetramer and higher polymer formed in the reaction. These dimers can be depolymerized and are therefore a convenient form of storage or shipping the monomer. In addition, the dimer is itself a valuable intermediate in chemical reactions such as in polymerization to form drying oils, resins, or rubbery polymers. While selective dimerization has been achieved with substantial success by control of reaction conditions the formation of polymer has nevertheless been a consistent problem in commercial applications of this reaction.

We have now discovered that lower conjugated dienes can be selectively dimerized with improved yields and reduced polymer formation by employing as a diluent a branched-chain paraffinic hydrocarbon or mixture of such hydrocarbons which are substantially odorless and free of aromatics and which boil in the range of 270 to 800° F., preferably in the range of about 335 to 500° F. We have found that this particular type of diluent, which is formed commercially as a product of HF alkylation of isobutane and butylenes, is unexpectedly superior to solvents previously employed as diluents in this re-

reaction rates as well as improved yields of the desired dimer and reduced formation of troublesome polymer.

It is an object of this invention to provide an improved process for the dimerization of conjugated dienes. It is another object of this invention to provide a method for selectively dimerizing conjugated dienes having from 4 to 6 carbon atoms per molecule. Still another object is to provide a method of dimerizing 1,3-butadiene to form vinylcyclohexene with increased reaction rates and reduced polymer formation. Other objects, advantages, and features of our invention will be readily apparent to those skilled in the art from the following description and the appendant claims.

While our invention is directed particularly to the formation of 4-vinylcyclohexene-1 by dimerizing 1,3-butadiene, it is applicable also to the selective dimerization of similar conjugated dienes known to be subject to thermal dimerization reactions to form cyclic compounds. Examples of such conjugated dienes, in addition to 1,3-butadiene, are isoprene, piperylene and conjugated dienes having 6 carbon atoms per molecule, for example di-propenyl and diisopropenyl. Mixtures of these conjugated dienes can also be reacted to form cyclic codimers.

The diluent which is employed according to the process of our invention is normally a mixture of paraffinic hydrocarbons which are highly branched although a single branched-chain paraffin having a boiling point in the range specified would be also suitable. The diluent to be employed is substantially free of aromatics. The preferred hydrocarbon mixtures have a minimum initial boiling point of about 335° F. and a maximum end boiling point of about 500° F. In the manufacture of vinylcyclohexene, we prefer to use as a diluent a branched-chain paraffin mixture boiling in the lower portion of this range, that is, having an initial boiling point of at least about 335° F. and a maximum end boiling point of about 410° F. For the benefit of further describing this diluent the following data is set forth which shows the typical properties of four commercially available special purpose hydrocarbon products of this type which are commonly known as odorless thinners. For purposes of reference in this specification these solvents are designated as diluents A, B, C and D. It should be understood that the following properties are typical only and should not be interpreted to limit unduly the identification of the hydrocarbon diluent which is employed in the practice of our invention.

Typical Properties	Diluent A	Diluent B	Diluent C	Diluent D	Test Methods
Initial Boiling Point, ° F.	349	354	424	399	ASTM D86-52.
End boiling point, ° F.	406	440	463	480	ASTM D86-52.
Refractive index at 20° F.	1.4217	1.4237	1.4315	1.425	
Bromine number	0.6	0.8	1.1	1.0	ASTM D1159-52.
Kauri-Butanol value, ml.	25.3	24.0	23.4	26.0	Gardner.
Aniline point, ° F.	185	186	198	186	ASTM D1012-51.
Flash point, TCC, ° F, 760 mm.	133	140	192	164	ASTM D56-52.
Color, Saybolt	+30	+30	+30	+30	ASTM D156-53T.

action. In addition to reducing the polymer formation in the production of vinylcyclohexene from 1,3-butadiene, this diluent permits greatly increased reaction rates, in the order of 2 to 2½ times that realized when employing the reaction product, vinylcyclohexene, as the solvent as is conventionally done. The reaction rates which can be obtained in the process of our invention even exceed those obtained when employing other inert solvents. We have found that when employing the diluent above described which boils in the lower portion of the range specified, namely from about 335 to 410° F., surprisingly high reaction rates can be realized. The use of this diluent in the process of our invention for the formation of vinylcyclohexene by dimerizing 1,3-butadiene enables high

60 The selective dimerization of our invention is carried out by mixing the conjugated diene with the diluent above described in a volume ratio of approximately ½ to 3 volumes of diluent per volume of diene. Somewhat less diluent than this can be employed with improved results and although greater amounts of diluent can be used, for economy of reactor capacity it is not advisable. In the manufacture of vinylcyclohexene we prefer to employ about equal volumes or approximately equal weights of diluent and butadiene.

65 The reaction mixture is then subjected to dimerizing conditions which are substantially those known and employed in the art. For example, suitable temperatures to effect selective dimerization are in the range of about

250 to 500° F. and at least sufficient pressure to maintain the reaction mixture in the liquid phase. In preparing vinylcyclohexene by this reaction we prefer to use a temperature between about 300 to 400° F. and a pressure in the range of approximately 100 to 500 pounds per square inch gauge. We have found that, in general, when employing the diluent specified for our invention, higher temperatures can be employed than are normally used with conventional diluents and polymer formation is still maintained at a low level. The reaction time can vary over a broad range, for example from a few (15 or 20) minutes in continuous reactions to several hours in batch processes, as high as 20 hours or more being desirable at times. Normally we prefer operations employing reactor residence times in the order of 1 to 5 hours. As the reaction proceeds additional diene can be fed to the reactor to maintain the pressure at the desired level. Another approach is to premix the butadiene and diluent, continuously feed the mixture to the reaction zone and withdraw effluent as the reaction proceeds. Separation of the dimer from the diluent can be effected by any suitable method, fractional distillation being preferred when boiling points differ sufficiently to make this means practicable. Dimers of the 5 and 6 carbon atom dienes will separate less readily from the preferred diluent by fractional distillation and other methods such as fractional crystallization can be employed.

To further describe the advantages and features of our invention the following examples are presented. The reactants and their proportions and other specific conditions are presented as being typical and should not be construed to limit the invention unduly.

EXAMPLE I

1,3-butadiene and highly branched paraffinic diluent corresponding to diluent A described above were premixed in a volume ratio of 1 to 1 and fed from a weighed bomb to a stainless steel reactor equipped with a mechanical stirrer, heating and cooling coils. The reactor had been purged with nitrogen and the reaction mixture was fed under a nitrogen pressure of 250 pounds per square inch gauge. A similar mixture of butadiene and vinylcyclohexene was prepared and processed in like manner. The results of these runs are reported below in Table 1 showing reactor conditions and yields. Reaction mixture was fed to the reactor to maintain a constant pressure and therefore feed rate is an indication of the rate of reaction of the butadiene.

Table 1

Run.....	1	2	3	4
Temperature, ° F.....	450	400	400	400
Pressure, pounds per square inch gauge.....	250	250	250	250
Diluent.....	Vinylcyclohexene	Diluent A	Diluent A	55
Residence Time, hours.....	3.6	3.2	2.5	2.5
Feed Rate, grams butadiene/hour.....	440	366	905	927
Yield, mol percent based on butadiene consumed:				
Vinylcyclohexene.....	52.8	68.3	71.2	78.7
Polymer.....	40.1	21.1	17.6	19.1

As shown from the above data the reaction rate obtained in the process of our invention was more than double that obtained by employing vinylcyclohexene as the diluent. In addition the yield of vinylcyclohexene was substantially increased and the production of polymer reduced markedly. This combination of advantages over the conventional process was totally unexpected.

EXAMPLE II

Mixtures of 1,3-butadiene and solvent were prepared in a 1 to 1 weight ratio and fed as described in Example I to a stainless steel reactor as fast as required to maintain the reactor pressure at 250 pounds per square inch gauge.

The reactor was maintained essentially liquid full during the runs. The solvents employed were two highly-branched paraffinic mixtures corresponding to diluents A and C described previously and Stoddard solvent, which is substantially a naphthenic mixture. Reactor temperature was maintained at 400° F. and the pressure at 250 pounds per square inch gauge. The reaction rate for these runs is shown in Table 2 below.

Table 2

	Diluent A	Diluent B	Stoddard Solvent
Reaction Rate, grams butadiene/hour.....	865	780	754

The data of Table 2 shows improved reaction rates over an inert naphthenic solvent which is reputed to be inferior to vinylcyclohexene because of increased polymer or gel formation. It is evident therefore from the data presented by these examples that a novel process employing a specific paraffinic solvent is made available for selective dimerization of conjugated dienes at high yields and reaction rates by the practice of our invention.

As will be evident to those skilled in the art, various modifications of this invention can be made, or followed, in the light of the foregoing disclosure and discussion, without departing from the spirit or scope thereof.

We claim:

1. A process for dimerizing lower acyclic dienes which comprises subjecting a lower acyclic conjugated diene to dimerizing conditions of temperature and pressure in the presence of a substantial amount of diluent consisting essentially of material selected from the group consisting of a branched-chain paraffinic hydrocarbon and mixtures of such hydrocarbons substantially free of aromatics and boiling in the range of 270 to 800° F.

2. A process for dimerizing lower acyclic dienes which comprises mixing an acyclic conjugated diene having from 4 to 6, inclusive, carbon atoms per molecule with a diluent consisting essentially of material selected from the group consisting of a branched-chain paraffinic hydrocarbon and mixtures of such hydrocarbons substantially free of aromatics and boiling in the range of about 335 to 500° F. and subjecting said diene in the presence of said diluent to dimerizing reaction conditions including a temperature in the range of about 250 to 500° F. and pressure at least sufficient to maintain the reaction mixture in the liquid phase.

3. A process for producing vinylcyclohexene which comprises dimerizing 1,3-butadiene in the presence of a diluent consisting essentially of material selected from the group consisting of a branched-chain paraffinic hydrocarbon and mixtures of such hydrocarbons substantially free of aromatics and boiling in the range of about 335 to 500° F.

4. A process according to claim 3 wherein said diluent has an initial boiling point of about 350° F. and an end boiling point of about 405° F.

5. In a process for the production of vinylcyclohexene by the dimerization of 1,3-butadiene the improvement which comprises subjecting said butadiene to dimerizing conditions including a temperature in range of 250 to 500° F. and a pressure at least sufficient to maintain the reaction mixture in the liquid phase for a reaction time between 2 and 40 hours in the presence of a diluent consisting essentially of material selected from the group consisting of a highly branched-chain paraffinic hydrocarbon and mixtures of such hydrocarbons substantially free of aromatics and boiling in the range of about 335 to 500° F., said diluent being present in an amount between about 1/2 to 3 volumes of diluent per volume of butadiene.

6. In a process for the preparation of vinylcyclohexene by dimerizing 1,3-butadiene the improvement which comprises subjecting a reaction mixture of butadiene and

diluent consisting essentially of material selected from the group consisting of a highly branched-chain paraffinic hydrocarbon and mixtures of such hydrocarbons substantially free of aromatics and boiling in the range of 350 to 405° F. in a volume ratio between about $\frac{1}{2}$ to 3 volumes of diluent per volume of butadiene to a temperature between about 300 and 450° F., a pressure sufficient to maintain the reaction mixture in the liquid phase and for a time in the range of about $\frac{1}{2}$ to 20 hours.

7. An improved process for preparing vinylcyclohexene which comprises mixing 1,3-butadiene with a paraffinic diluent in a volume ratio of about $\frac{1}{2}$ to 3 volumes of diluent per volume of butadiene, said diluent consisting essentially of material selected from the group consisting of a highly branched-chain paraffinic hydrocarbon and mixtures of such hydrocarbons substantially odorless and free of aromatics and boiling in the range

of 350 to 405° F., subjecting the mixture of butadiene and diluent to a temperature between about 300 to 450° F., and sufficient pressure to maintain a liquid phase for from about 1 to 5 hours, and distilling the reaction mixture to recover said vinylcyclohexene.
